PHOTOGRAPHIC DEVELOPING APPARATUS

Filed Feb. 3, 1922

UNITED STATES PATENT OFFICE.

JACOB SUMTER, OF NEW YORK, N. Y.

PHOTOGRAPHIC-DEVELOPING APPARATUS.

Application filed February 3, 1922. Serial No. 533,751.

To all whom it may concern:

Be it known that I, JACOB SUMTER, a citizen of the United States, residing at New York, county of Queens, State of New York, have invented certain new and useful Improvements in Photographic-Developing Apparatus, of which the following is a specification.

The principal object of this invention is to provide improved apparatus for treating photographic films without handling them or exposing them to the light and without the necessity of using a dark room. The film with its protective paper is wound on a revolvable drum. The lower portion of the drum dips into a bath of the proper solution, so that when the drum is revolved the various parts of the film are passed through the bath. The drum and the tank holding the bath are contained in a box which is light proof except for an inspection window of non-actinic glass. A feature of the apparatus is that it is so constructed that the liquid in it can be changed without the necessity of removing the tank or opening the box. The drum can carry any length of film up to its capacity as well as films of various widths. Simplicity of construction is also an important object.

I attain these objects by the mechanism illustrated in the accompanying drawing.

Figure 1 is a plan of the top of my device. Figure 2 is a vertical longitudinal section through the apparatus taken along the line 2—2 of Figure 3. Figure 3 is a cross section taken along the line 3—3 of Figure 2. Figure 4 is a front elevation.

Mounted in a casing or box 1 is the drum 2 which consists of two circular plates 3 carried by a flanged sleeve 4; the circular plates 3 carrying near their edges a series of rolls 5. Shaft 6 is rotatably mounted in box 1 and carries fixed to it sleeve 4 of drum 2. On one end of shaft 6 is fastened the crank 7. When crank 7 is turned drum 2 is revolved. The lower side of drum 2 dips into tank 8 which holds the developing or fixing bath.

Rolls 5 which are rotatably mounted between plates 3, are formed with two diameters, the central portion being of a smaller diameter than the two end portions. This is to enable films of different widths to be used. The narrower films fit on the smaller diameter central portion while the wider

ones span across the central portion and are carried by the end portions.

The film cartridge 28 is placed in drum 2 and is rotatably held between plates 3 by the usual spring mechanism for holding film cartridges in cameras. Drum 2 also carries a reel 9 upon which tape 10 is adapted to be wound. Tape 10 is led from reel 9 between guide rollers 26 over rolls 5 up to a point where the catch 11 at its end is fastened to the protecting paper of film 12. Pin 13 is held in a bearing rotatably mounted in the right hand plate 3. This bearing serves to hold one end of reel 9 and with pin 13 acts to serve as a winding key as is common in roll film cameras. Knob 14 is mounted in the wall of box 1 at the same radial distance out from the center of shaft 6 as is reel 9. Knob 14 has a smaller central shank portion enabling it to be moved in and out from the face of box 1. When knob 14 is pushed in, its inner end is adapted to engage pin 13 on reel 9. Turning knob 14 causes reel 9 to turn. When it is desired to hold knob 14 out of engagement with reel 9, leaf 15 carried by box 1, is turned down so as to rest on the shank of knob 14.

Box 1 carries an orange or red glass window 16 to enable the operator to observe conditions inside the apparatus when in use. At the top of box 1 is located a hinged door 17, while at the side just above tank 8 is a door 18. Door 18 is held in place by a removable rod 19, which is adapted to slide through rings 20, the two end ones being fastened to box 1 and the central one to door 18.

To the lower end of tank 8 is fastened a drain-pipe 22 provided with stop-cock 21. An inflow pipe 23 carrying funnel 24 is located adjacent to the upper end of tank 8.

In operation, the door 17 is lifted open and the film cartridge 28 is inserted in drum 2. The protecting paper of the cartridge is unwound a bit and passed between guide rolls 25. Tape 10 is caused to pass over rolls 5 by holding one end of it in the hand and turning drum 2 by crank 7 until the end of the protecting paper is reached. Tape 10 is then fastened to the protecting paper by means of catch 11. Drum 2 is then rotated so as to bring reel 9 opposite knob 14. Knob 14 is pushed in to engage pin 13, leaf 15 having first been lifted. Now

door 17 is closed. Knob 14 is now rotated so as to wind tape 10 on reel 9 until the entire length of film 12 with its protecting paper is wrapped around drum 2 ready for 5 developing. Knob 14 is then pulled out and locked in its outer position by pressing down leaf 15. Developing solution is introduced into tank 8 through funnel 24 and pipe 23. Drum 2 is now rotated by turning crank 7 10 until the desired amount of development is obtained. Drip plates 27 are provided to lead back any of the solution lifted out of the tank.

Opening stop-cock 21 drains off the developing solution. Washing water is now introduced into tank 8 through funnel 24 and drum 2 is revolved again long enough to wash the film. Instead of introducing just enough of the washing water to fill the 20 tank and keeping stop-cock 21 closed, the washing can be effected by letting the water constantly flow in through the funnel and empty out through the open stop-cock.

After the washing, the fixing solution is 25 introduced into the tank and the drum rotated until the fixing is completed. After going through the washing operation again, the film is removed from the apparatus.

I claim:

30 1. In a photographic developing apparatus, the combination of a casing, a revolvable drum in said casing, means for rotatably mounting a film cartridge on the drum, a reel rotatably mounted on said drum, a length of flexible material adapted to be wound on said reel and around said drum, said length having fastening means enabling it to pull on the film, whereby when the reel is rotated the film is caused to be pulled around said drum.

45 2. In a photographic developing apparatus, a casing, a revolvable drum in said casing, said drum having its periphery formed by a plurality of spaced rolls, each of said rolls being formed with a shank having a plurality of diameters to admit of films of different widths being wound on the drum and means for winding the film on said drum while the casing is closed.

50 3. In a photographic developing apparatus, the combination of a casing, a revolvable drum in said casing, means for wrapping the film around said drum without opening the casing, a tank adapted to hold a bath into which said drum dips whereby as said drum is rotated successive portions of the film are passed through the bath and separate inflow and outflow devices provided for said tank adapted to permit charging or discharging without the necessity of tilting the tank.

60 4. In a photographic developing appa-

ratus, the combination of a casing, a revolvable drum in said casing, means for wrapping the film around said drum without opening the casing, a tank adapted to hold a bath into which said drum dips whereby as said drum is rotated successive portions of the film are passed through the bath, and means in operative relation to 70 said tank suitably constructed to permit charging and discharging of the tank without the necessity of tilting it. 65

5. In a photographic developing apparatus, the combination of a casing, a revolvable drum in said casing, means for wrapping the film around said drum without opening the casing, a tank adapted to hold a bath into which said drum dips whereby as said drum is rotated successive 80 portions of the film are passed through the bath, and means in operative relation to said tank suitably constructed to permit a continuous flow of fluid through the tank. 75

6. In a photographic developing apparatus, the combination of a casing, a revolvable drum in said casing, means for wrapping the film around said drum without opening the casing, a tank adapted to hold a bath into which said drum dips 90 whereby as said drum is rotated successive portions of the film are passed through the bath, an inflow provided with a funnel and an outflow provided with a stop-cock in operative relation to said tank for charging 95 and discharging it. 85

7. In a photographic developing apparatus, the combination of a casing, a revolvable drum mounted in said casing, said drum having its periphery formed by a plurality of spaced rolls, means for rotatably mounting a film cartridge on the drum, a reel rotatably mounted on said drum and a length of tape adapted to be wound on said reel, said tape carrying fastening means enabling it to pull on the film, whereby when the reel is rotated the tape causes the film to be pulled around said drum and unwound from the cartridge. 100 105

8. In a photographic developing apparatus, the combination of a casing, a revolvable drum in said casing, means for rotatably mounting a film cartridge on the drum, a reel rotatably mounted on said drum, a length of flexible material adapted to be wound on said reel and around said drum, said length carrying fastening means enabling it to pull on the film, whereby when the reel is rotated the film is caused to be pulled around said drum and a rotatable handle, mounted in said casing adapted to move into and out of engagement with said reel, for rotating said reel. 110 115 120

JACOB SUMTER.
